(57) **CLAIM**

The ornamental design for a strap, as shown and described.

DESCRIPTION

FIG. 1 is a top, front, right perspective view of a strap showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view of a strap shown in an exemplary environment.

The strap is shown with a symbolic break in its length. The appearance of any portion of the strap between the break lines forms no part of the claimed design. The even-length broken lines form no part of the claimed design. The zig-zag lines represent stitching and form no part of the claimed design. The even-length broken lines in FIG. 8 of the exemplary environment form no part of the claimed design.
